UNITED STATES PATENT OFFICE.

GEORGE R. WIMBERLY, OF MOUNTAIN PARK, OKLAHOMA.

DOOR-OPERATING DEVICE.

1,207,458.

Specification of Letters Patent.

Patented Dec. 5, 1916.

Application filed November 15, 1915. Serial No. 61,615.

To all whom it may concern:

Be it known that I, GEORGE R. WIMBERLY, a citizen of the United States, residing at Mountain Park, in the county of Kiowa and State of Oklahoma, have invented new and useful Improvements in Door-Operating Devices, of which the following is a specification.

The invention relates to a door operating device, and more particularly to the class of combination door openers and locks.

The primary object of the invention is the provision of a device of this character wherein a door or doors will be automatically unlatched and opened when a vehicle, truck or the like travels on to a runway, and subsequently the doors will close and latch on the vehicle, truck or the like leaving the runway.

Another object of the invention is the provision of a device of this character wherein the construction thereof is novel in form to assure the positive locking of the doors closed and also for the automatic operation thereof under the influence of a load upon a vehicle, truck or the like.

A further object of the invention is the provision of a device of this character which is simple in construction, readily and easily applied to a door frame and doors of the sliding type, thoroughly reliable and efficient in operation, strong, durable and inexpensive in manufacture and installation.

With these and other objects in view the invention consists in the features of construction and the combination and arrangement of parts hereinafter described, illustrated in the accompanying drawings and pointed out in the claim.

In the drawings: Figure 1 is a plan view of a door frame and sliding doors in closed position, with the device constructed in accordance with the invention applied; Fig. 2 is a view looking toward the inner side of the door frame and doors; Fig. 3 is a sectional view on the line 3-3 of Fig. 1; Fig. 4 is a sectional view on the line 4-4 of Fig. 1; Fig. 5 is a detail perspective view of one of the latch members.

Similar reference characters indicate corresponding parts throughout the several views of the drawings.

Referring to the drawings in detail, A designates generally a door frame which, in this instance, is slightly elevated above a foundation or flooring and B a pair of slid-

ing doors which are mounted upon a track C by means of roller hangers D of any standard form so that the doors can be moved for the opening and closing thereof, while secured to the inner edges of the vertical stiles of the door frame A at the sill thereof are bearings 10 in which are journaled the crank ends 11 of rocking levers 12 which have the free ends of their longer stretches coöperative with latches herein-after fully described. Arranged for vertical sliding movement next to and at the inner sides of the vertical stiles of the door frame A are operating rods 13 which are formed at their upper ends with eye terminals 14 loosely engaging pivot ends 15 of the short stretches of the operating rods 13, the said rods being extended through suitable openings in the foundation or flooring at the inner side of the door frame A and are fixed in a depressible rail 16 which is located beneath the foundation or flooring contiguous to the sill of the door frame A to form a bearing for a runway herein-after fully described.

The latches each comprise a pair of spaced parallel cheeks 17 which are suitably fixed to the inner side of the door and between these cheeks of the said latches are pivoted substantially L-shaped latch arms 18 which are adapted to engage keeper pins or lugs 19 carried by the said doors B to normally lock the doors in closed position, the said arms 18 being formed with cam extensions 20 against which operate the longer stretches of the arms 12 which play between the cheeks 17 so that on the swinging movement of the said arms 12 the extensions 20 will be acted upon for automatically releasing the latch arms 18 and thereby unlock the doors. On continued further movement of the arms 12 the doors will be automatically moved to open position.

Connected to the pivot ends 15 of the short stretches of the arms 12 are coiled retractile springs 21 which are also connected to the vertical stiles of the door frame A so that when pressure is relieved from the rail 16 the springs 21 will become inactive for automatically closing the said doors.

The runway comprises a gangplank 22 which is formed with slots 23 in which are arranged tread bars 24 swingingly supported upon pivots 25, and these bars have protruding ends 26 beyond the plank 22 so as to engage upon the rail 16 for depressing

the same when a vehicle travels on to the bars 24, whereby the weight of the load of the vehicle, truck or the like will effect the automatic unlatching of the doors and the movement of the same to open position. When the vehicle, truck or the like leaves the bars 24 the pressure upon the rail 16 is relieved, whereupon the springs 21 will effect the automatic closing of the doors and the latching of the same. It will be apparent that when a vehicle travels into the inclosure through the door frame the doors are automatically unlatched and opened and on the vehicle leaving the inclosure the said doors will close and become automatically latched.

From the foregoing description, taken in connection with the accompanying drawings, the construction and manner of use of the device will be readily understood and a more extended explanation has, therefore, been omitted.

Having thus described my invention, I claim:

25. The combination with a gangboard hav-

ing depressible sections forming a trackway, of a door frame, a pair of sliding doors mounted for opening and closing the doorway, depressible sections mounted at one side of the doorway and alining with the 30 depressible sections of the gangboard, a vertically movable bar supporting the free ends of the sections at one side of the doorway and also the sections in the gangboard, resilient means connected with said bar to 35 normally hold the same elevated, levers pivoted to the doorway and also having connection with the doors and operated upon by movement of the bar, latch devices normally locking the doors closed and operated 40 upon by the levers for releasing the same, and guide cheeks on the doors and having pins for contact by the levers.

In testimony whereof I affix my signature in presence of two witnesses.

GEORGE R. WIMBERLY.
